UNITED STATES PATENT OFFICE.

CYRUS KINNEY, OF DEREHAM TOWNSHIP, OXFORD COUNTY, CANADA.

IMPROVEMENT IN SASH-FASTENERS.

Specification forming part of Letters Patent No. 157,452, dated December 8, 1874; application filed October 23, 1874.

CASE B.

To all whom it may concern:

Be it known that I, CYRUS KINNEY, of the township of Dereham, in the county of Oxford, in the Province of Ontario, Canada, have invented an Improved Sash Holder and Fastener, of which the following is a specification:

This invention relates to an improvement in sash holders and fasteners for the purpose of more effectually securing the upper and lower sashes when closed, or of adjusting and maintaining them when open at any required height.

I attach two suitably-notched strips of metal or other suitable material, A, of the shape shown in accompanying drawing, by means of screws passing through their upper ends to the sides of the sashes, one being fixed to the upper sash, and the other to the lower. The lower ends of these swinging strips of metal are allowed to work freely backward and forward on the screw B in their upper end, and from their construction will always lie against the stop C unless held back. On the faces of the swinging strips next the stop a series of notches or teeth, D, is formed, and on the stop, at any required height, studs or catches E E¹ E² E³ are fixed, which arrest and fix the swing-

ing strips or holders A in the following manner:

In the accompanying drawing, the lower sash is shown closed, with the holder A resting against the stop C, and engaging in its lower notch with the stud or catch E. In this position the sash remains locked until the swinging holder is drawn back by means of the point F, and the sash may then be raised, and at any required height the holder will maintain it by one or other of its notches or teeth engaging with catch E¹, or, if the window is opened to its full height, with the catch E³. The upper sash and its notched swinging holder work in a precisely similar manner by engaging with the catch E².

I claim as my invention—

The notched metal strips A A', constructed as shown, and moving freely on the screws B B', in combination with the catches E E¹ E² E³, when attached to the sash and sash-stop, substantially as and for the purpose described.

CYRUS KINNEY.
